PHOTO-TUBE

Earl D. Wilson, Wilkinsburg, Pa., assignor to
Westinghouse Electric & Manufacturing Com-
pany, a Corporation of Pennsylvania

Application July 5, 1929. Serial No. 376,115

2 Claims. (Cl. 250—27.5)

This invention relates to photo-tubes and particularly to the construction and method of supporting the electrodes thereof.

It is an object of this invention to provide a cathode for a photo-tube of such form that the effect of the shadow of the other electrodes upon the cathode shall be minimized.

It is a further object of my invention to provide a photo-tube with a shield grid and a control grid and to so arrange the supports for the elements that the shield grid shall be, as far as possible, unaffected by any mechanical vibration.

Other objects of my invention and details of the construction will be apparent from the following description and the accompanying drawing, in which

Figure 1 is a central vertical section, and Fig. 2 is a horizontal section.

The photo-tube is very similar to that shown in my copending application, Serial No. 341,344, filed February 20, 1929, for an improvement in Shielded anode photo-tubes, the present application being for an improvement upon the photo-tube illustrated in said copending application.

The photo-tube has the usual transparent envelope 1, provided at the lower end, with a press 2 through which extend connections for the anode 3, the shield grid 4 and the cathode 5. The anode is a vertical centrally located rod which is connected through the press with a pin 6, which is one of four pins, properly located to cooperate with a standard receiving socket. The shield grid 4 is supplemented by a disc 7 at the upper end and a sleeve 8 at the lower end similar in purpose and construction to the corresponding parts in said copending application.

The shield grid is supported by a standard 9, by which it is connected to a disc 10, the connection being made through a support 12, which extends through the press 2 and connects the shield grid 4, disc 7, sleeve 8, and disc 10 to the external pin 13.

The cathode 5 is in the form of a tube or cylinder supported by two uprights 15 and 16, which are connected with standards mounted in the press 2. Both uprights extend through openings in the disc 10. The standard 17, connected to upright 15, extends through the press 2 and connects the cathode with the external pin 18. Another standard 19, connected to upright 16, extends into the press 2 but not through it.

Both uprights extend above the upper end of the cathode 5 and are there connected by a bead 20, which also connects a standard 21 and a supplemental brace 21^A together and to the uprights

15 and 16, but insulates them therefrom. Standard 21 extends through an upper press 24, and connects the external metallic cap 25 with the control grid 26. Preferably, the standard 21 is offset in order to afford room in the bead 20 for the brace 21^A. A rod 22 is welded to standard 21 and brace 21^A and bead to extend along the control grid 26 and is secured thereto at numerous points.

During the construction of the tube, the material for coating the cathode is deposited in a capsule 27 on the under side of disc 10. This material is volatile. When the tube has been pumped and sealed, it is subjected to a high frequency alternating electro-magnetic field which produces eddy currents in the metallic parts. The disc 10, being a closed circuit in effective position to be energized by the field, carries relatively heavy eddy currents and is, consequently, heated more than the other metallic elements of the tube. The photo-electric material in the capsule 27 is thereby evaporated and distills away from the disc 10.

The material will be deposited mainly upon the glass envelope 1, but, as the device is heated in a furnace after this operation, the material distills from the wall 1 on to the relatively cool cathode 5. By this process, very uniform and readily controlled coating is deposited on the inner face of the cathode. If the capsule 27 were on the side of the disc 10 toward the cathode, the material would distill directly from the disc on to the cooler cathode and a less even deposit would result.

In the operation of the device, light is received through the opening which extends longitudinally of the cathode and is reflected from the inner surface of the cylindrical cathode. This opening is approximately 90° of the circumference of the hollow cylindrical cathode as disclosed in Fig. 2. Several, and sometimes many, reflections of the light occur before it again emerges through the opening. The photo-electric effect is produced each time that the light impinges upon the cathode, consequently, the many reflections largely counteract the defect of the presence of opaque elements, including the anode 3, the two grids and their supports. In this way, a very effective photo-tube is provided, which is but slightly sensitive to mechanical jar.

Although I have illustrated and described but a single modification, many variations of my invention will readily occur to those skilled in the art. The omission of any specific description of these was not intended as a limitation, the

only intentional limitations being those required by the prior art, or indicated in the claims.

I claim as my invention:

- 5 1. A photo-tube comprising a plurality of concentric electrodes, photo-electric material on one end of said electrodes, a press at one end of said tube, supports extending from said press for said electrodes, a second press at the opposite end of said tube, a control grid, and a support extending 10 from said second press for said grid, said last mentioned support also insulatingly supporting the one of said electrodes having photo-electric material thereon.

2. A photo-tube comprising a hollow cylindrical cathode, photo-electric material on said cathode supporting members extending along elements of the cathode, a press in which said supporting members are mounted, a second press, a support mounted in said second press rigidly connected to and insulated from said supporting members, and extending within said cathode and an electrode carried by said support. 80 85
